US0D1101156S

(12) **United States Design Patent** (10) **Patent No.:** **US D1,101,156 S**
(45) **Date of Patent:** **** Nov. 4, 2025**

(54) **MONITORING APPARATUS**

(71) Applicant: **VivaQuant, Inc**, Arden Hills, MN (US)

(72) Inventors: **Brian Brockway**, St. Paul, MN (US);
Garrett Charles Duffy, St. Paul, MN (US)

(73) Assignee: **VivaQuant, Inc**, Arden Hills, MN (US)

(**) Term: **15 Years**

(21) Appl. No.: **29/907,856**

(22) Filed: **Jan. 9, 2024**

(51) LOC (15) Cl. **24-02**

(52) U.S. Cl.

USPC **D24/167**; D24/168; D24/186; D24/187
